(57) CLAIM

The ornamental design for a packaging sheet, as shown and described.

DESCRIPTION

The file of this patent contains at least one drawing executed in color. Copies of this patent with color drawing(s) will be provided by the Office upon request and payment of the necessary fee.

FIG. 1 is a top plan view of a packaging sheet in accordance with a first embodiment of our new design.

FIG. 2 is a top plan view of a packaging sheet in accordance with a second embodiment of our new design.

FIG. 3 is a top plan view of a packaging sheet in accordance with a third embodiment of our new design.

FIG. 4 is a top plan view of a packaging sheet in accordance with a fourth embodiment of our new design.

FIG. 5 is a top plan view of a packaging sheet in accordance with a fifth embodiment of our new design.

FIG. 6 is a top plan view of a packaging sheet in accordance with a sixth embodiment of our new design.

FIG. 7 is a top plan view of a packaging sheet in accordance with a seventh embodiment of our new design; and,

FIG. 8 is a top plan view of a packaging sheet in accordance with an eighth embodiment of our new design.

The depicted surface of the packaging sheet in each of the FIGS. 1-8 is flat, the design not visible from the opposite back view of the packaging sheet.
